UNITED STATES PATENT OFFICE.

HIRAM G. SEDGWICK, OF MILL VALLEY, CALIFORNIA, ASSIGNOR TO THE NATIONAL SAFETY APPLIANCE COMPANY, A CORPORATION OF CALIFORNIA.

TRAIN-STOPPING DEVICE.

1,164,758.

Specification of Letters Patent. Patented Dec. 21, 1915.

Application filed November 22, 1912, Serial No. 732,985. Renewed May 17, 1915. Serial No. 28,771.

To all whom it may concern:

Be it known that I, HIRAM G. SEDGWICK, a citizen of the United States, and a resident of Mill Valley, county of Marin, State of California, have invented certain new and useful Improvements in Train-Stopping Devices, of which the following is a full and clear specification, reference being had to the accompanying drawings, in which is represented a vertical longitudinal sectional view of my improved valve apparatus.

The object of this invention is to provide a simple pneumatic apparatus which will be controlled and operated by a fluid pressure source on one of the vehicles of the train; the preferred construction being such that said fluid pressure will be utilized to not only normally hold the brake setting devices out of action but will also serve to actuate the brake setting devices when the brake is to be applied. I have illustrated my fluid pressure motor mechanism as applied to a brake setting vent valve for air brakes but it will be understood that in its broadest aspects the invention includes the idea of combining my motor with any type of brake setting devices, even an electric braking means.

A further object of the invention is to so construct the apparatus that I avoid the use of all stuffing boxes, which are undesirable in view of the fact that unless the apparatus is frequently used the packings stick and thus endanger the proper operation of the apparatus.

In the drawing, *a* designates a small pipe which at its end is provided with a vent valve *b* which is adapted to be operated in any suitable manner by the automatic mechanism which cooperates with the road bed actuating means. An instance of one way of actuating this valve *b* is illustrated in my co-pending application Serial Number 733,162. This pipe *a* is connected at its upper end to the left hand end of the cylinder *c* in which operates a piston valve *d*. This piston valve is preferably constructed as shown with a pair of cup leathers. At the right hand end of cylinder *c* is a smaller cylinder *e* which is open at its left hand end to the cylinder *d* and at its right hand end to the atmosphere. In this cylinder *e* works another piston valve *f* which is connected by a stem *g* to the piston *d*. A port *h* extends axially through the stem *g* and con-

ncts at its inner end with a radial port *i* 55 formed in the piston *d*.

The port *i* connects, when the piston *d* is in its normal position, which is the position shown in the drawing, with a port *j* which extends to the right hand end of cylinder *c* 60 serving as a head for the cylinder *k*. Another port *l* is formed in the cylinder *c* and communicates with the interior thereof at opposite sides of the piston *d* when the same is in normal position. This port *l* extends through the wall of the cylinder *k* to a port *m* which is in communication with the main air reservoir *n* by a pipe *o*, whereby a main reservoir pressure is constantly exerted on both sides of piston *d*. A port *p* 70 extends from inlet *m* to the left hand end of cylinder *k*, and this port *p* is regulated as to area by means of a screw valve *q*.

The left hand end of cylinder *k* is closed by a head *r* and this head is provided with a cylinder *s*, one end of which opens to the atmosphere and the other end of which opens into cylinder *k*. Working in this cylinder *s* is a piston *t* which is connected by a rod *u* to a larger piston *v* working in cylinder *k* 80 and normally resting at the right hand end thereof. As will be seen, reservoir pressure through port *p* holds piston *v* at the right hand end of cylinder *k*; the interior of this cylinder at the right of the piston being in 85 communication with the atmosphere through ports *j*, *i* and *h*.

Connected to piston *t* and fitting cylinder *s* is a tube *w* which is provided with a vending slot or slit *x* extending longitudinally of it and also with one or more vent holes *y* at suitable points along the length of the tube. The end of the tube opposite the piston *t* is provided with a pair of pistons *a'* and *b'*, the former being slightly larger than the latter. The piston *b'* is practically equal in diameter to the tube *w* and is attached to the extreme end thereof, while the piston *a'* is a little larger and is supported a short distance in front of the piston *b'* by means of a rigid connecting rod *c'* smaller in diameter than the tube *w*. The piston *a'* works in a cylinder *d'* at a point beyond a port *e'* which is connected to the air brake pipe by means of pipe *f'*, so that train pipe pressure is 105 always maintained in the smaller chamber between the two pistons *a'* and *b'*. The piston *b'* fits in the adjacent head of the cyl-

inder d' and serves to close the same, while the piston a' closes the other end of the cylinder d' . The piston b' being less in diameter than the bore of cylinder d' , when said piston together with tube w is pushed into cylinder d' , the brake pipe is vented through the slot x in the tube w , thus applying the train brake. The use of a slot x in the tube insures a gradual or service application of the brakes.

10 The fluid pressure reservoir n is in communication with the left hand end of cylinder c by means of a pipe g' and the aforesaid pipe a , a check valve h' being employed at 15 the juncture of these two pipes. The valve h' is adapted to be opened manually so as to permit main reservoir pressure to be admitted into pipe a . When the main reservoir pressure has thus been admitted into pipe a , 20 all the parts will assume the position shown in the drawing and the brake setting mechanism will be ready for actuation, which will occur when valve b is opened to exhaust or partially exhaust the front end of cylinder c 25 through pipe a .

When the valve b is opened, the reduction in pressure in the forward end of cylinder c permits reservoir pressure to quickly throw piston d forwardly. This forward movement instantly closes the forward branch of port l and thus cuts off reservoir pressure from in front of piston d , and this movement also cuts off the rear end of cylinder k , by closing port j , from the atmosphere. 35 Further movement of piston d puts the rear end of cylinder c in communication with the rear end of cylinder k thorough port j , whereupon reservoir pressure will enter behind piston v . This will force piston v to the forward end of the cylinder k by reason of the fact that there is a greater area of the piston exposed to pressure at the rear than at the front side of the piston, the difference being equal to the area of the cross section of the 45 rod u . The speed with which this piston moves forwardly will be determined by the size of the outlet port p as controlled by the screw valve q . As this forward movement takes place the piston b' will pass into the cylinder d' and thus exhaust the train or brake pipe f' out through one or more of the ports x and y . The speed with which the exhaust slot x enters the tube d' will determine the time period for applying the brakes of 55 the train. I prefer using the long narrow slot port x when this invention is applied to an air brake system since in that manner I provide for a service application of the brakes as distinguished from an emergency stop.

To restore the parts to normal position, it is simply necessary to open check valve h' to permit reservoir pressure to enter the forward end of cylinder c , whereupon all the 65 parts will return to normal through the

pushing of the piston d back to the rear end of this cylinder and the venting of the rear end of cylinder k through ports j , i and h . It will be observed therefore that I employ main reservoir pressure for holding the 70 brake setting means in position for actuation and also for positively actuating said brake setting means. The advantage of using the pilot differential valve devices (consisting of the piston d and its coöperating parts) is 75 that the mechanism may be put into operation by the venting of but a very small modicum of air, since it will require but a very little air to be exhausted from the forward part of cylinder c to shift the predominating pressure to the rear side of piston d .

It will be observed also that with the present apparatus it is unnecessary to use stuffing boxes at any point, these stuffing boxes 85 being undesirable in that unless frequently used they become dried and consequently cause the rods to stick. These stuffing boxes are also objectionable upon an apparatus of this sort in that should they be tightened up 90 too much they will render the apparatus inoperative, thus permitting a disobedient engineer or other mischievously inclined person to put the apparatus out of commission. While I prefer avoiding the use of stuffing 95 boxes, it will be understood however that the invention in its broader aspect may be carried into effect with an apparatus in which stuffing boxes are employed. It will be observed also that while I prefer to use 100 air as the fluid motive power, I may in some cases employ steam or liquid without departing from the spirit of my invention.

Having thus described my invention, what I claim as new and desire to secure by Letter Patent, is—

1. In a train stopping apparatus, a brake setting means, a differential fluid pressure motor for actuating the brake setting means and also for restoring the brake setting means to normal, and a common fluid pressure reservoir for causing both these movements, means being provided for constantly subjecting to reservoir pressure the low pressure side of the piston to thereby normally hold the brake setting means inoperative.

2. In a train stopping apparatus, a brake setting means, a differential fluid pressure motor for actuating the brake setting means 120 and also for restoring the brake setting means to normal, and a common fluid pressure reservoir for causing both these movements, said motor embodying a differential main piston and a differential pilot valve device.

3. In a train stopping apparatus, a brake setting means, a differential fluid pressure motor for actuating the brake setting means and also for restoring the brake setting 130

means to normal, and a common fluid pressure reservoir for causing both these movements, said motor embodying a differential main piston and a differential pilot valve device, said pilot valve device embodying a differential piston.

4. In an automatic train stopping apparatus, a valve for venting the train pipe, a differential pneumatic motor for opening and closing the valve and means for operating said motor by main reservoir air in both its opening and closing movements, means being provided for constantly subjecting to reservoir pressure the low pressure side of the piston to thereby normally hold the brake setting means inoperative.

5. In an automatic train stop, the combination of a vent valve in the train pipe, a pneumatic motor for positively opening and closing said valve and normally holding it closed, and a pneumatically controlled valve mechanism for reversing the normal action of the motor to thereby open the vent valve, this valve mechanism embodying means for holding its valve open by main air reservoir pressure.

6. In a train stopping apparatus, a valve for venting the train pipe, a motor for operating said valve consisting of a differential arrangement of pistons and cylinders, the cylinders both being normally open to main air reservoir pressure, and means for venting one of the cylinders to reverse the differential pressure on the piston therein to thereby cause the motor to operate said vent valve.

7. In a train stopping apparatus embodying a valve for venting the train pipe, means controlled by direct main reservoir air pres-

sure for positively opening and closing said valve, said means embodying a motor cylinder, a differential piston working therein and having its low pressure side connected to the venting valve, and means whereby reservoir pressure is constantly admitted to the 45 low pressure side of the piston.

8. In a train stopping apparatus, the combination of a brake setting means, a main cylinder, a supplemental cylinder carried by one of the heads of the aforesaid cylinder, a 50 differential piston working in said main cylinder, a rod connected to this piston and provided with a smaller piston working in said supplemental cylinder, this smaller piston being connected to the brake setting means, means for transmitting fluid pressure to the opposite sides of said main piston, and valve mechanism for controlling the admission and exhaust of fluid to and from said main cylinder.

9. In a train stopping apparatus, brake setting devices and fluid pressure means for positively actuating and restoring said brake setting devices, said means embodying a cylinder and differential piston, means connecting the piston to the brake setting devices, means whereby fluid pressure is constantly admitted to the side of lesser pressure of said piston, a pilot valve device for controlling admission of air to the other side of 70 said piston and pneumatic means for controlling this pilot valve device.

In testimony whereof I hereunto affix my signature in the presence of two witnesses.

HIRAM G. SEDGWICK.
